UNITED STATES PATENT OFFICE.

CHARLES J. EDMONDS, OF GRAND CROSSING, ILLINOIS.

LIQUID-FUEL BURNER.

SPECIFICATION forming part of Letters Patent No. 443,670, dated December 30, 1890.

Application filed June 10, 1889. Serial No. 313,797. (No model.)

To all whom it may concern:

Be it known that I, CHARLES J. EDMONDS, a citizen of the United States, residing at Grand Crossing, in the county of Cook, State 5 of Illinois, have invented certain new and useful Improvements in Liquid-Fuel Burners, of which the following is a full, clear, and exact description, reference being had to the accompanying drawings, forming part of 10 this specification.

My present invention has for its object to provide an improved liquid-fuel burner which may be conveniently inserted into and withdrawn from the stove in connection with 15 which it is to be used, and, further, to provide an improved construction of burner, by means of which a more effective distribution and burning of the fuel will be secured.

To this end my invention consists in the 20 novel features of construction, hereinafter described, illustrated in the accompanying drawings, and particularly pointed out in the claims at the end of this specification.

Figure 1 is a perspective view of a cooking- 25 stove embodying my invention, parts being broken away for the purpose of better illustration. Fig. 2 is an enlarged view in vertical transverse section through the top of the stove, the delivery-pipe being shown as ex- 30 tended through the cross-bar. Fig. 3 is an enlarged detail plan view of the pan of the burner. Fig. 4 is an enlarged plan view of the burner with the distributor in place there- 35 in. Fig. 5 is an enlarged view in vertical transverse section on line 5 5 of Fig. 4.

A designates the main body of a stove or range in connection with which my invention is especially well adapted for use, the stove or range being shown as provided with the 40 usual top formed of the movable cross-bar B and the lids C. In one of the lids C is formed a perforation, preferably at its center, through which passes the delivery-pipe D, to the upper end of which is connected a suitable oil- 45 reservoir E, and the portion of this delivery-pipe D that extends into the body of the stove is preferably jointed, as at d and d', and has connected to its inner end the burner F. The lid C, through which the fuel-delivery pipe 50 passes, is preferably screw-threaded, and a corresponding thread is formed upon the exterior of the delivery-pipe to engage with the

threaded perforation of the lid, although, if desired, the delivery-pipe may be connected in any other convenient manner with the lid. 55 From the construction as thus far defined it will be seen that the burner is sustained by the lid C, so that it can be readily inserted into and removed from the stove merely by lifting the stove-lid either through the me- 60 dium of the upper portion of the delivery-pipe D or by a suitable stove-lifter inserted into the usual lifting-socket c, formed in the upper surface of the lid. By this construction it becomes unnecessary to perforate the side 65 walls of the stove for the insertion of the delivery-pipe of the burner, or, in fact, to modify in any respect the construction of the stove further than to perforate its lid or cross-bar, and hence when it is not desired to employ 70 the burner it can be readily removed from the stove, and a plain imperforate lid can be employed. So, also, when the burner is sustained by the lid, it can be readily shifted to different points within the stove by merely 75 turning the lid either by means of a suitable lid-lifter or by grasping the upper portion of the delivery-pipe D. Moreover, as the lids of cooking-stoves and ranges are made of standard sizes, it is plain that the same size burn- 80 ers can readily be applied to various styles and sizes of stoves without the necessity of making special patterns therefor.

My improved construction of burner comprises an expanded open-topped pan, in the 85 bottom of which is formed a suitable perforation to receive the upwardly-turned end of the delivery-pipe D, the perforation of the pan and the end of the pipe being preferably screw-threaded to enable the parts to be se- 90 curely connected together. Upon the inner face of the pan G adjacent its bottom are formed suitable lugs or ribs g, on which will rest the distributor H, the lugs serving to hold the distributor at such distance from the inner 95 face of the pan that a free distribution of the oil between the pan and the distributor is secured. The distributor consists, preferably, of a lower dish-shaped plate having upon its inner face adjacent its sides suitable lugs h, 100 upon which will rest the upper plate H', these plates being shown as attached by a bolt I, and by preference the inner faces of the plates H H' (one or both) are provided ad-

- jacent the bolt-holes with hubs or bosses h' , which serve to better hold the plates separate and prevent their collapse under the intense heat to which they will be subjected.
- 5 The plates H H' are preferably each furnished with slots or perforations H^2 , and to fill the space between these plates asbestos or like fire-resisting material is conveniently used, which will serve to take up the oil as 10 it is delivered into the pan G and hold the same in condition to be readily ignited and burned. From this construction it will be seen that if oil is admitted through the delivery-pipe D into the pan G the asbestos 15 filling between the plates H H' will readily take up the oil, so that on applying a match to the upper face of the plate H a ready ignition of the fuel will be secured, combustion occurring not only over the upper surface of 20 the plate H' , but also around the space between the pan G and the edges of the distributor-plate H .
- When it is desired to employ more than one burner, these may be conveniently sustained 25 from the cross-bar B of the stove, as seen in Fig. 2 of the drawings, in which event the cross-bar will be suitably perforated to receive the delivery-pipe D , the lower end of this delivery-pipe being extended in opposite direction 30 to sustain the burners F . Any desired number of burners may thus be sustained from a movable part of the cover of the stove or range in such manner that they can be quickly placed therein or removed therefrom.
- 35 When my improved liquid-fuel burners are to be applied in connection with boiler or other furnaces, it will be merely necessary to attach a series of branch pipes to a main fuel-delivery pipe, such branch pipes being similar 40 in construction to the lower portion of the fuel-delivery pipe above described. If any of the burners become worn or broken, these can be readily replaced by simply unscrewing from the end of the pipe and substituting new burners instead.

Having thus described my invention, what I claim as new, and desire to secure by Letters Patent, is—

1. A liquid-fuel burner comprising an open distributing-pan, a fuel-delivery pipe connected to said pan, and a distributor loosely held within said pan, said distributor consisting of perforated plates H and H' , united together independently of the distributing-pan, whereby the distributor can be readily 55 removed, and having an interposed mass of incombustible material—such, for example, as asbestos—substantially as described.

2. A liquid-fuel burner comprising an open distributing-pan having lugs or ribs upon its 60 upper surface to sustain the distributor, a fuel-delivery pipe connected to said pan, and a distributor loosely held within said pan upon said lugs or ribs, said distributor consisting of perforated plates united together 65 independently of the pan and adapted to receive an interposed mass of incombustible material, substantially as described.

3. A liquid-fuel burner comprising an open distributing-pan, a fuel-delivery pan connected to said pan, and a distributor loosely held within said pan, said distributor consisting of perforated plates H and H' , united together with their outer edges abutting and forming an intermediate space to receive a 75 mass of incombustible material, substantially as described.

4. A liquid-fuel burner comprising a pan having a perforated bottom and open top, a fuel-delivery pipe connected to said pan, and 80 a distributor formed of perforated plates having suitable spacing-lugs on their inner faces and a bolt for uniting said perforated plates, substantially as described.

CHARLES J. EDMONDS.
